REINFORCED RAIL

Filed May 2, 1931

INVENTOR
Paul W. Dillon.

By: Charles K. Miller

UNITED STATES PATENT OFFICE

PAUL W. DILLON, OF STERLING, ILLINOIS

REINFORCED RAIL

Application filed May 2, 1931. Serial No. 534,587.

This invention has to do with rails, and more particularly of the character providing tracks for railway cars and the like.

It is one of the important objects of this invention to provide a rail of this character embodying means for reenforcing the same particularly against bending stresses.

Another object of the invention is to provide track construction wherein the portions of the rails bridging the ties are reenforced to resist bending stresses.

A further object of the invention is to provide means affording maximum reenforcement for rails, said means being of such a character that it requires a minimum of weight.

Another object of the invention is to provide truss- or arch-shaped reenforcing means for rails.

In accordance with the general features of the invention, in the formation of the rail, the same is rolled and simultaneously provided with integral waving or zig-zagging ribs on its web, and the rails thus formed are preferably laid over the ties so that adjacent rib portions are located symmetrically between adjacent ties and are arranged truss-wise, that is, like an inverted U or V, to thereby offer maximum resistance to bending of the rail between adjacent ties. By providing ribs, it will be apparent that the weight of the rails is only very slightly increased, while the reenforcing effect of the ribs is very substantial.

Further important objects and advantages of this invention will be apparent from the disclosures in the drawing and specification.

The invention, in preferred forms, is illustrated on the drawing and hereinafter more fully described.

Figure 1 is a fragmentary sectional view showing one form of rail constructed in accordance with the present invention and mounted on a plurality of ties, the rail being shown in elevation.

Figure 2 is a view similar to Figure 1, but showing a modified rail construction.

Figure 3 is an enlarged fragmentary sectional view taken approximately in the plane indicated by the line III-III of Figure 1.

Figure 4 is an enlarged fragmentary sectional view taken approximately in the plane indicated by the line IV-IV of Figure 2.

Referring now more particularly to the drawing, wherein the same parts are indicated throughout by the same reference characters, the rail 1 is shown mounted on ties 2, the web 3 of the rail having formed preferably integral therewith a continuous waving or zig-zagging rib 4 on each side thereof. It will be noted that the track or rail 1 is so located with respect to the ties 2, that the adjacent rib portions 6 are arranged in the form of an inverted U or V substantially symmetrically between adjacent ties 2, so that said portions 6 together constitute a substantially truss- or arch-like reenforcing structure which is highly resistant to bending of the portion of the rail between adjacent ties 2, the stresses being caused by pressure of the wheels passing thereover. Allowing for the proper factor of safety, of course, the rib portions 6 are arranged to offer maximum resistance to bending at the middle of each rail span, which is the location of the greatest bending stress.

In Figures 2 and 4, the base portions 8 of the rib portions 9 are connected by the rib portion 10 extending substantially parallel to the rail 11, the ends of the base portions 8 being disposed substantially in alignment with the sides 12 of the ties 2. The ties 2 being spaced apart the same distance in both figures, it will be apparent that the rib portions 9 meet adjacent the upper portion of the web 13 in a truss-like structure which is substantially more acute than the corresponding structure of Figure 1. This provides for a more pronounced bracing and reenforcing effect of the rib portions 9. While the rib portion 10 does not provide the reenforcing effect which is true of the base portions 7 of the structure of Figure 1, yet it will be evident that the portion of the rail carrying the rib portion 10 is not subject to as great a bending stress as the portions of the rail located over the spaces between the ties, so that the construction of Figure 2 will serve to adequately reinforce and brace the rail 11.

It will be seen from the foregoing that I have provided a rail structure embodying means for resisting the bending stresses to which a rail is subject during the passage of cars thereover without materially adding to the weight of the rail.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

15. 1. A track structure comprising a plurality of spaced ties, a rail carried by said ties, and reenforcing means carried by said rail where said rail bridges the space between said ties, said means having an inverted V-shaped truss-like formation.
20. 2. A track structure comprising a plurality of spaced ties, a rail carried by said ties, and reenforcing means carried by said rail where said rail bridges the space between said ties, said means having an inverted V-shaped truss-like formation, the bases of said formation being positioned over said ties.
25. 3. A track rail having a zig-zag reenforcing rib extending longitudinally along its web, spaced ties for supporting said rail, the inverted substantially V-shaped portions of said rib being disposed over the spaces between said ties.
30. 4. A track rail having integral reenforcing means comprising a plurality of spaced ribs, each in the form of a substantially inverted V, other ribs extending parallel to the length of the rail and connecting juxtaposed ends of said ribs, and spaced ties supporting said rail, the first ribs being located over the spaces between said ties, whereby to reinforce the rail against bending stresses.
35. 5. A track rail having integral reenforcing means comprising a plurality of spaced ribs, each in the form of a substantially inverted V, other ribs extending parallel to the length of the rail and connecting juxtaposed ends of said ribs, and spaced ties supporting said rail, the first ribs being located over the spaces between said ties, whereby to reinforce the rail against bending stresses, said ribs being narrow relative to the width of said rail, to thereby provide maximum reenforcing means with a minimum of additional weight.

In testimony whereof I have hereunto subscribed my name at Sterling, Whiteside County, Illinois.

PAUL W. DILLON.
